US00D800207S

(12) **United States Design Patent** (10) **Patent No.:** **US D800,207 S**
Harrison et al. (45) **Date of Patent:** **** Oct. 17, 2017**

(54) **CAMERA MOUNT**(71) Applicant: **GoPro, Inc.**, San Mateo, CA (US)(72) Inventors: **Ryan Harrison**, El Granada, CA (US);
Mark E. Costa, Menlo Park, CA (US);
Seungheon Lee, Cupertino, CA (US);
Richard Gioscia, Santa Clara, CA (US);
Soyun Kim, Seoul (KR);
Matthew D. Thomas, Castro Valley, CA (US); **Danilo Bueno**, Burlingame, CA (US)(73) Assignee: **GoPro, Inc.**, San Mateo, CA (US)(**) Term: **15 Years**(21) Appl. No.: **29/561,949**(22) Filed: **Apr. 21, 2016****Related U.S. Application Data**

(63) Continuation of application No. 29/526,262, filed on May 7, 2015, now Pat. No. Des. 758,474.

CLAIM

The ornamental design for a camera mount, as shown and described.

DESCRIPTION

FIG. 1 is a front, top, and right side perspective view of a camera mount;

FIG. 2 is a rear, bottom, and left side perspective view thereof;

FIG. 3 is a left side elevational view thereof;

FIG. 4 is a right side elevational view thereof;

FIG. 5 is a rear elevational view thereof;

FIG. 6 is a front elevational view thereof;

FIG. 7 is a top plan view thereof; and,

FIG. 8 is a bottom plan view thereof.

The broken lines in the drawings are included for the purpose of illustrating environmental structure and form no part of the claimed design.

1 Claim, 8 Drawing Sheets# US D800,207 S
